UNITED STATES PATENT OFFICE.

ALBERT E. ROBINSON AND AUGUSTUS M. SOSA, OF CINCINNATI, OHIO, ASSIGNEES TO THE AMERICAN TOOL WORKS COMPANY, OF CINCINNATI, OHIO, A CORPORATION OF OHIO.

DRILLING MACHINE.

Application filed February 21, 1925. Serial No. 10,947.

Our invention relates to means for driving the drill-spindle of a drilling machine at a plurality of selective speeds, and is an elaboration upon the mechanism disclosed in Letters Patent of the United States No. 1,297,256, granted March 11, 1919, on the application of H. W. Schatz and A. M. Sosa, for improvements in drilling machines.

In the device of said patent a relatively small gear is associated with the drill-spindle for rotating the drill-spindle at high speeds, and a relatively large gear, exemplified as an internal gear, is associated with the drill-spindle for rotating the drill-spindle at relatively slow speeds, these relatively high speeds and relatively slow speeds being multiplied by speed changing mechanism.

We have found it desirable under certain conditions to dissociate the relatively large gear from the drill-spindle and its driving means, for instance when employing the drill-spindle for tapping or threading small holes and similar or other operations in which it is desirable to rotate the drill-spindle at the higher range of speeds and to reverse the rotations of the drill-spindle in rapid sequences.

We have also found it advantageous under such relations and during performance of such functions to maintain the relatively large gear stationary, and we have further found it advantageous to provide the relatively large gear with elongated bearing means comprising a plurality of axially arranged ball-bearings about the drill-spindle, which aids in centering the relatively large gear about the drill-spindle when the drill-spindle is rotated through the medium of said relatively large gear, and aids in maintaining axial alinement of the relatively large gear with the drill-spindle when said relatively large gear is dissociated from rotational connection with the drill-spindle or held in stationary position.

It is the object of our invention, therefore, to provide means whereby such respective advantages may be obtained; further, to provide a relatively small gear and a relatively large gear about a drill-spindle and novel means whereby the relatively large gear is rotatively dissociated from the drill-spindle and its driving connections; further, to provide means whereby rotation of the relatively large gear is arrested or held sta-

tionary upon rotative dissociation thereof from the drill-spindle; and, further, to provide novel means in mechanism employing a gear of comparatively small diameter and a gear of comparatively large diameter about a spindle for rotating the latter, and means whereby the gear of comparatively large diameter about the spindle is supported in non-rotative relation thereto when employing the gear of comparatively small diameter for imparting rotations to the spindle.

Our invention will be further readily understood from the following description and claims, and from the drawings, in which latter:

Fig. 1 is a side elevation, partly in section and partly broken away, showing a drill-head mounted on the radial-arm of a radial drill, and embodying our invention.

Fig. 2 is a central vertical axial cross-section of the same.

Fig. 3 is a horizontal cross-section of a detail of the same, taken in the plane of the irregular line 3-3 of Fig. 2, exemplifying a rotative reversing mechanism.

Fig. 4 is an enlarged axial vertical cross-section of an exemplification of our improved device, taken in the plane of the line 4-4 of Fig. 6, showing the internal gear in driving relation.

Fig. 5 is a similar view, showing the internal gear in dissociated relation.

Fig. 6 is a horizontal cross-section of our improved device, taken in the plane of the line 6-6 of Fig. 4, and partly broken away.

Fig. 7 is a detail in vertical section, taken on the line 7-7 of Fig. 6.

Fig. 8 is an axial vertical cross-section, showing a modification of our improved device, and taken in the plane of the line 8-8 of Fig. 9.

Fig. 9 is a horizontal cross-section of the same, taken in the plane of the line 9-9 of Fig. 8.

Fig. 10 is a detail in section on the line 10-10 of Fig. 8.

Fig. 11 is a horizontal sectional detail, taken in the plane of the line 11-11 of Fig. 8; and,

Fig. 12 is a detail of the braking means taken in section on the line 12-12 of Fig. 8.

We have exemplified our invention as applied in a radial drilling machine, such as disclosed in the aforementioned patent, in-

cluding a radially extending drill-arm 21 extending radially from the usual column, rotatable about the usual post, extending vertically from the usual base.

Referring to Figs. 1 to 7 inclusive, a drill-head 25 is adjustable lengthwise on the drill-arm and supports the drill-spindle 26, and driving and feeding mechanism therefor. The drill-head supports a usual drilling tool, 10 or may have a tapping-tool 27 therein, arranged to thread a previously drilled hole in a piece of work 28 on the table 29 of the machine.

The driving and feeding mechanism is actuated by a usual cross-shaft 31, extending lengthwise of the drill-arm, and rotated in usual manner by means of driving mechanism at the column, usually including speed changing mechanism, all as more fully described in said aforementioned patent.

The drill-head is adjustable lengthwise of the drill-arm and the cross-shaft on guideways 32, 33, by usual means, for instance, as more fully shown and described in the aforementioned patent.

The drill-spindle is rotatable in a non-rotatable sleeve 35, sliding in a bearing 36 on the drill-head, end-abutment bearings 37, 38, being located between the sleeve and the 30 drill-spindle. The mechanism for feeding this sleeve, and consequently the drill-spindle endwise by hand or by power is usual, but preferably such as is more fully described in the aforementioned patent.

35 A sleeve 41 surrounds the spindle and has connection therewith so as to rotate the same, as by providing the spindle with a spline-groove 42 and providing a key 43 therein having connection with the sleeve, permitting axial movements of the spindle in the sleeve. The sleeve is journaled in a bearing 44 in the drill-head.

The mechanism for rotating the drill-spindle comprises a gear of comparatively small 45 diameter, exemplified as an external spur-gear 51, and a gear of comparatively large diameter, exemplified as an internal gear 52. The external gear is fixed to the sleeve, as by a key 53. The sleeve is held axially in 50 its bearing 44 between said last-named gear and a step-bearing 54 located between an annular shoulder 55 on said sleeve and an annular shoulder 56 on said bearing 44. The pinion 57, shown fixed to the sleeve, is the 55 initial gear of a usual train of power feeding gears for feeding the spindle axially, not more particularly shown.

The external gear and the internal gear are arranged to be driven at various speeds, 60 for imparting high speed ratios of rotation to the drill-spindle when driven through the medium of said external gear, and for imparting low speed ratios of rotation to the drill-spindle when driven through the medium of said internal gear.

The internal gear is exemplified as of inverted cup-shape and provided with an upper substantially close web 58 between the hub and the teeth of the gear.

A pair of axially movable gears is located 70 between the external gear and the internal gear, and is arranged to be meshed with either. Thus a gear 61 is arranged to coact with the internal gear and a gear 62 is arranged to coact with the external gear, the 75 axes of rotation of these gears being located in the space between the teeth of the internal gear and the external gear.

The gears 61, 62, are fast with a sleeve 63, journaled in a bushing 64. The bushing has 80 axial movement in a bearing 65 for selective engagement of the gear 61 with the internal gear 52 or of the gear 62 with the external gear 51. The bushing is preferably non-rotative in its bearing. A spline key 66 is held 85 axially to the bushing and is received in a spline groove 67. Part of this spline groove is in said bushing and a mating part thereof is in the bearing 65. (See Fig. 4).

A shaft 71 is journaled in a bearing 72 in 90 the drill-head. The sleeve 63 has spline-key and groove connection 73 with said shaft, for maintaining rotative driving connection between them at the various positions of the sleeve on its shaft. The gear 61 may be 95 moved into the bearing 65 when the driving gear 62 is caused to mesh with the external gear.

The shaft 71 is arranged to have various 100 speeds imparted thereto, which are transmitted either to the low speed or to the high speed gearing about the spindle, for imparting variable speeds to either the low speed or high speed gearing thereabout.

For accomplishing this a variable-speed 105 driving connection is provided between the shaft 71 and a shaft 75. This variable-speed driving connection is instanced as comprising a plurality of spaced-apart gears 76, 77, 110 of different diameters, fixed to the shaft 71. 115

Gears 79, 80, fast with a sleeve 81, are arranged to be selectively brought into meshing relation with the gears 76, 77, as by moving said sleeve lengthwise on the shaft 75, parallel with the shaft 71, said sleeve having 115 spline-key and groove connection 82 with said shaft.

The shaft 75 is journaled in bearings 83 in the drill-head and is arranged to be driven in opposite directions.

120 Power reversing mechanism is included in the train of driving mechanism for the drill-spindle between the cross-shaft and the gearing in the drill-head, and is instanced as comprising friction reversing mechanism.

The shaft 75 is provided with a bevel-gear 85 fixed thereto. Bevel-gears 86, 87, are arranged to be placed in mesh with the bevel-gear 85 at opposite sides of the latter, for selectively rotating the bevel-gear 85, 130

and consequently the drill-spindle, in opposite directions by means of the cross-shaft 31, or permitting said bevel-gear and spindle to remain at rest.

5 The friction reversing mechanism exemplified comprises a sleeve 91, exemplified as having spline-key and groove connection 92 with the cross-shaft, and arranged to be moved lengthwise of the cross-shaft with the 10 drill-head, as by being journaled in bearings 93 on the drill-head. The gears 86, 87, are instanced as loosely mounted on the sleeve, with suitable friction clutching means between said sleeve and each of said gears, 15 exemplified as comprising clutch-bands 94, 95, between said bevel-gears and hubs 96, 97, fixed to said sleeve, whereby the gears may be selectively connected with said sleeve by expanding the clutch-bands of the respective 20 clutches.

The clutch-bands are arranged to be selectively expanded by a key 98 acting upon suitable expanding levers 99, 100, for expanding the friction bands in well-known manner, 25 and so arranged that shifting of the key to expand one or the other of the clutch-bands will release the opposite clutch-band so as to be automatically returned to non-clutching position. The key is shifted axially of 30 the sleeve 91 by a manually oscillated rod 101, the operating handle 102 of which extends to convenient position of the operator.

The oscillating rod is provided with an arm 103, having articulation at 104 with a 35 fork 105, slidable laterally on the shaft 106 in bearings 107 of the drill-head, the fork being received in an annular groove 108 in a collar 109, movable in axial directions on the sleeve 91 and secured to the key 98 by 40 a screw 110.

The selective driving connections between the shaft 71 and the drill-spindle, and between the shafts 71 and 75, are preferably independently controlled by mechanism 45 adapted to be manually actuated. Instancing this arrangement, the sleeve 63 is arranged to be moved axially on the shaft 71 for meshing the gear 61 with the internal gear 52, or the gear 62 with the external gear 51. The proximate ends of the teeth of the 50 gears 61, 52, are preferably tapered, as shown at 111, 112, for avoiding clashing of said gears.

This sleeve is exemplified as slidable axially on the shaft 71 by means of a fork 115, received in an annular groove 116 formed in the hub of the gear 62, the fork being fixed to a sleeve 117, slidable axially on a rod 118, fixed in the drill-head. This sleeve 55 has a rack 119 thereon, engaged by a segment-gear 120, on a rocker-rod 121, journaled in the drill-head and having a segment-gear 122, fixed thereon.

The latter segment-gear is meshed by a 60 rack 123, on a lengthwise movable rod 124,

slidable in a guideway 125, in a housing 126 on the drill-head, and having a rack 127 thereon. This latter rack is engaged by a segment-gear 128, fixed to a shaft 129, with which a handle-arm 130 is rigidly connected, 70 the shaft being journaled in the housing. The handle-arm comprises a yieldable pull-handle 131, which moves across and is arranged to be held in selective positions on an arc-piece 132.

The sleeve 81 is arranged to be moved axially on the shaft 75, by being provided with an annular groove 135, in which a fork 136 is received, the fork being operated in manner similar to the operation of the fork 115, by a handle-arm 137, having a resilient pull-handle 138 thereon, and arranged to be placed in selective positions along the arc-piece 132, the construction and operation being similar to the construction and operation 80 of the means for axially moving the sleeve 63, and all as more fully shown and described in the aforementioned patent.

The axial movement of the sleeve 81 engages the gear 79 with the gear 76, or the 90 gear 80 with the gear 77, for imparting a plurality of speeds to the shaft 71, and amplifying the number of speeds of the sleeve 63, and multiplying the speeds imparted by 95 the latter to the drill-spindle.

In order to support the gear 52 in such manner that it may be connected with the sleeve 41 or dissociated therefrom, we provide said gear with an elongated hub 141, in which there is a shell 142, fixed thereto, spaced-apart ball-bearings 143, 144, being located between said gear and its sleeve. These ball-bearings are combined radial and 100 end-thrust bearings.

The outer raceways of the ball-bearings are separated by a thimble 145, and the inner raceways thereof are separated by a thimble 146. A nut 147, received about the upper threaded end 148 of the sleeve, clamps the inner raceways and the thimble therebetween to an annular shoulder 149 on said sleeve. This nut is exemplified as having an annular protecting flange 150 extending therefrom above the ball-bearings to guard 110 the same against dust and dirt.

A cover-housing 161 is received above the internal gear, and forms a cover for the drill-head, the same being provided with an opening 162 through which the spindle extends.

There is a clutching means between the 120 sleeve 41 and the internal gear, exemplified as a clutch-collar 164 about the sleeve, connected with the sleeve by spline-key and groove connection 166, and provided with clutch-teeth 167, arranged to engage mating clutch-teeth 168 on the shell 142 of the internal gear. The proximate ends of the clutch-teeth are preferably beveled, as shown at 169, 170, to avoid clashing of the teeth.

A clutch-lever 171, shown in the form of 130

a yoke received about the clutch-collar, is pivoted on a pin 172 to a lug 173 secured to the web 174 of the drill-head.

The arms of the yoke-lever are provided with pins 175 having rollers 176 thereon located in an annular groove 177 in the clutch-collar, forming an operative connection between the clutch-lever and the clutch-collar.

The clutch-collar is operated in unison with the speed changing mechanism for driving the spindle by means of the external gear or the internal gear in such manner that, when the internal gear is arranged to do the driving, the clutch is placed in engagement and when the external gear is arranged to do the driving, the clutch mechanism is in disconnected relation.

Means are also preferably provided whereby the operation of the clutch is automatically accomplished by the shifting mechanism for effecting speed-change. Thus the sleeve 63 is provided with a projection 179, this projection being shown as an extension of the key 66, which is arranged to engage the lever 171 for swinging the latter on its pivot and causing clutch engagement.

Release of the clutch is caused by movement of the sleeve in the opposite direction. This releasing movement may be accelerated by means of a plunger 181, operable in a socket 182 in the clutch-lever, and provided with a shank 183, guided in a hole 184 in the clutch-lever, a spring 185 in said socket surrounding said shank to normally urge the plunger outwardly for release of the clutch.

In the form shown, in Figs. 1 to 7 inclusive, the clutch-collar and the clutch-lever are located within the internal gear.

Means are also preferably provided for arresting rotation of the gear of comparatively large diameter, namely, the internal gear, when the latter is unclutched, exemplified as accomplished by a brake 187, shown comprising a brake-shoe 188 fixed to the clutch-lever, and arranged to engage a coacting annular face 186 on the web 58 of the internal gear, so as to stop rotation of the internal gear when the clutch is unclutched, this stopping being substantially instantaneous. The brake-shoe may be secured to the lever 171 by screws 189. The brake-shoe is urged toward the web of the internal gear by the spring 185 acting on the plunger 181, which engages the web 174 of the drill-head.

In the modification shown in Figs. 8 to 12 inclusive, the comparatively large gear is provided with clutching means at its upper end. The various parts of the clutching means and of the mounting means for the internal gear are similar to those hereinbefore described, the various parts being designated by similar reference numerals raised to the series 200.

The clutch-lever 271 is shown provided with a fork received about the clutch-collar.

The lever is pivoted on bolts 272 in lugs 273 depending from the cover-housing 261.

The lever is further provided with a fork 278, with which a projection 279 on the sleeve 63 is articulated. This projection is shown in the form of a shank secured to the sleeve 63 by screws 291, and movable axially in a guideway 292 in the bearing 265, in which the sleeve has axial movement, thus preventing rotation of the sleeve. The articulation between the lever and said extension comprises a pin 293 in said extension, having slide-blocks 294 thereon, received in slots 295 in said fork.

The brake 287 is shown comprising a brake-shoe 288, received in a socket 290 in a plunger 281, movable axially in a socket 282 in said clutch-lever. The plunger is provided with a shank 283 extending through a hole 284 in said clutch-lever, a spring 285 in the socket 282 normally urging the brake-shoe toward the internal gear. The brake-shoe coacts with a coacting annular face 286 on the internal gear. A nut 296 is threaded about the threaded end of said shank, the adjustment of the nut limiting the movement of the brake-shoe toward the internal gear.

When the gear 61 is moved out of mesh with the internal gear, as shown in Fig. 8, the clutch for said internal gear is moved out of clutching relation and the braking means therefor is moved into engaging relation, for arresting rotation of the internal gear. When the gear 61 is moved into mesh with the internal gear, the braking mechanism is first released, thereby permitting ready meshing between said gears, especially when the teeth thereof are provided with mating end tapering faces, and the coacting teeth of the clutch means are also engaged, which is readily accomplished, especially if the proximate ends of said teeth are tapered, the engagements of said gears and said clutch connecting the internal gear with the driving means and the sleeve about the spindle for driving the spindle.

Our improved device forms ready and convenient means for placing the drill-spindle under the influence of either a high speed range of rotative speed changes, or a low speed range of rotative speed changes, and, when placed under said high speed range of rotative speed changes, the gear of comparatively large diameter, represented as the internal gear, which is the final gear in the train of gearing for relatively low speed range of rotations for the spindle, is disconnected from said spindle and from its driving agencies, and its rotation is further arrested, whereby the strains upon the trains of mechanism, which would be due to such rotations of said comparatively large gear acting either upon the spindle or the driving means therefor, are removed, also relieving the reverse friction means, which are

the most sensitive elements in the gear train, from such strains, thereby maintaining the accuracy and sensitiveness in said reverse friction means and prolonging the life of the same.

Having thus fully described our invention, which we claim as new, and desire to secure by Letters Patent, is:

1. In a drilling machine, the combination of a drill-spindle, a gear of comparatively small diameter and a gear of comparatively large diameter about the axis of rotation of said drill-spindle, means operatively connecting said gears with said drill-spindle for rotating the latter, speed-change gearing for said gears for driving the latter at various speeds, means operatively dissociating said gear of comparatively large diameter from said spindle and from said speed-change gearing, and braking means for said gear of comparatively large diameter.

2. In a drilling machine, the combination of a drill-spindle, a gear of comparatively small diameter and a gear of comparatively large diameter about the axis of rotation of said drill-spindle, means operatively connecting said gears with said drill-spindle for rotating the latter, driving means for said gears comprising power reversing mechanism and speed-changing gearing between the latter and said gears, means operatively dissociating said gear of comparatively large diameter from said spindle and from said driving means, and means arresting rotation of said gear of comparatively large diameter when the latter is so dissociated.

3. In a drilling machine, the combination of a drill-spindle, a sleeve thereabout rotatively connected with said drill-spindle, an external gear of comparatively small diameter and an internal gear of comparatively large diameter about said sleeve, means rotatively connecting said first-named gear with said sleeve, clutching means between said sleeve and said second-named gear, a clutch-lever therefor, speed changing means for said gears comprising a pair of axially arranged gears of different diameters arranged to mesh by axial movements with said respective first-named gears, and means for moving said gears axially, said last-named means arranged for operative connection with said clutch-lever for operating the latter.

4. In a drilling machine, the combination of a drill-spindle, a sleeve thereabout rotatively connected with said drill-spindle, a gear of comparatively small diameter and a gear of comparatively large diameter about said sleeve, means rotatively connecting said first-named gear with said sleeve, clutching means between said sleeve and said second-named gear, speed changing means for said gears comprising a movable member, a clutch-lever for operating said clutch,

and braking means for said second-named gear, said movable member arranged for operative connection with said clutch-lever and said braking means for engagement of said clutching means and relief of said braking means by movement of said movable member in one direction and relief of said clutching means and engagement of said braking means by movement of said movable member in the opposite direction.

5. In a drilling machine, the combination of a drill-head, a drill-spindle therein, a sleeve about said drill-spindle having connection with said drill-spindle for rotating the latter, an external gear of comparatively small diameter and an internal gear of comparatively large diameter about said sleeve, means rotatively connecting said first-named gear with said sleeve, clutching mechanism between said sleeve and said internal gear comprising an axially movable collar about said sleeve, a lever pivoted to said head and having operative connection with said collar, speed-changing gearing for said first-named gears comprising a movable member having operative connection with said lever, and braking means for said internal gear having operative connection with said movable member.

6. In a drilling machine, the combination of a drill-spindle, a sleeve thereabout having connection therewith for rotating the same, an external gear fixed to said sleeve, an internal gear rotative about said sleeve, speed-change means for said gears comprising a movable member, and a clutch and lever for operating the same located within said internal gear, said clutch arranged for clutching engagement with said internal gear, and said movable member arranged for operative connection with said lever.

7. In a drilling machine, the combination of a drill-spindle, a sleeve thereabout having connection therewith for rotating the same, an external gear fixed to said sleeve, an internal gear rotative about said sleeve, speed change means for said gears comprising a movable member, a clutch between said sleeve and said internal gear, a lever for operating said clutch, and a brake on said lever for said internal gear, said movable member arranged to operate said lever.

8. In a drilling machine, the combination of a drill-spindle, a sleeve thereabout rotative therewith, an external gear fixed to said sleeve, an internal gear provided with an elongated hub about said sleeve, axially spaced ball-bearings between said hub and said sleeve, clutching means between said sleeve and said internal gear at one end of said ball-bearings, and speed-change means for said gears, said speed-change means comprising a movable member arranged for operative connection with said clutching means for operating the latter.

9. In a drilling machine, the combination of a drill-spindle, a sleeve thereabout having connection with said drill-spindle for rotating the latter, a bearing in said head for said sleeve, an external gear fixed to said sleeve, an internal gear about said sleeve, clutching means between said sleeve and said internal gear comprising a collar having rotative connection with said sleeve, a yoke-lever about said collar having connection therewith for axially moving said collar, speed-change means for said gears comprising a movable member arranged for clutch operation, and resilient means for said lever acting counter to the latter.

10. In a radial drilling machine, the combination of a horizontal drill-arm, a driven shaft extending lengthwise of said arm, a drill-head slideable laterally on said arm, a

drill-spindle journaled therein, a gear of 20 comparatively small diameter and a gear of comparatively large diameter about the axis of rotation of said drill-spindle, means operatively connecting said last-named gears with said drill-spindle for rotating the latter, speed-change gearing on said drill-head arranged for operative connections with said last-named gears for driving the latter, means operatively dissociating said gear of comparatively large diameter from said drill-spindle and from said speed-change gearing, and friction reversing mechanism between the said speed-change gearing and said shaft.

25 In testimony whereof, we have hereunto signed our names.

30 ALBERT E. ROBINSON.
AUGUSTUS M. SOSA.
